UNITED STATES PATENT OFFICE.

JULIUS DORNETH, OF BERLIN, GERMANY, ASSIGNOR TO TYPOGRAPH G. M. B. H., OF BERLIN, GERMANY.

MATRIX-SETTING AND LINE-CASTING DEVICE.

1,091,643.

Specification of Letters Patent. Patented Apr. 28, 1914.

Application filed April 4, 1910. Serial No. 553,272.

To all whom it may concern:

Be it known that I, JULIUS DORNETH, a subject of the German Emperor, residing at Berlin, S. W., in Germany, have invented, 5 certain new and useful Improvements in Matrix-Setting and Line-Casting Devices, of which the following is a specification.

In matrix setting and line casting machines with matrix bars guided on wires, the 10 matrix bars, for the purpose of obtaining mixed composition, are usually stopped in front of the matrix assembling channel by means of a stop, and then brought, by means of a bar, to the level corresponding to the 15 kind of type which is being set. In order to facilitate manipulation, the raising of the bar for leveling the matrices according to my invention, is effected simultaneously with the withdrawal of the stop by the depression 20 of the space key.

In the accompanying drawing—Figure 1 is a side elevation of a linotype machine embodying my invention; Fig. 2 a sectional plan view thereof; Fig. 3 an elevation 25 viewed in the direction of the arrow I, Fig. 2; Fig. 4 a plan detail view having parts shown in Fig. 2 removed; Fig. 5 a section on line A—B, Fig. 4; Fig. 6 an elevation viewed in the direction of arrow II, Fig. 4; 30 Fig. 7 a detail view. Fig. 8 a section on line 8—8, Fig. 2, Fig. 9 a detail-view of parts shown in Figs. 1 and 2.

By referring to these drawings, it will be noted that A, the matrix frame, is rigidly 35 supported on the shaft 1, said shaft being journaled in bearings 22 which are mounted on the frame B of the machine. The matrix frame A may be thrown upward from the working position represented in Fig. 1, by 40 grasping the handle 6. By striking one of the keys 2, Fig. 1, the corresponding matrix bar 4 which is sustained at the upper end of the matrix frame A is released through the medium of a connecting rod or wire 3. 45 Thereupon, it travels along one of the guide rods or wires 5 to the assembling position in a manner well understood, this operation being continued until a line of matrices has been assembled, whereupon the same is arranged opposite the mold in proper way, and a line cast therefrom. Thereupon, by 50 grasping the handle 6 and rocking the shaft 1 upwardly in its bearing, all of the matrix bars assembled, having been previously released for this purpose, are carried back by

gravity on the guide rods or wires 5 in the well-known way, being thus automatically distributed.

The matrix bars 4 are arranged for casting mixed type and, for this purpose, are 60 provided with two matrix characters 12 and 13, as shown in Figs. 3, 5 and 7, arranged one above the other on one edge of the matrix bar. The upper matrix character 12 may, for example, be for ordinary type, while the 65 lower characters 13 may be for printing distinguishing type. If mixed type is to be set up, it is necessary to raise the matrices for such distinguishing type, after they have been assembled, so as to bring the characters 70 13 into the casting line, before the matrices are brought opposite to the casting position, and before the following ordinary type are set up. This raising operation is performed by the mechanism hereinafter described. 75

On the fixed frame B there is arranged a guide strip 6 adapted to engage with one or the other of two notches 8 8¹ on the matrix bar, the said strip 6 engaging with the notch 8 if the character 12 is to be cast and 80 with the notch 8¹ if the character 13 is to be cast.

To raise a group of matrix bars, when mixed copy is to be cast, the following combination of parts is arranged: The coupling-rod 16 (see Figs. 1 and 2), is provided at or 85 near its lower end with a thumb disk or cam 17 adapted to bear against a slide or carriage 19 mounted on the frame B of the machine. The matrix-cage is actuated by 90 the coupling-rod 16 and the thumb disk in the manner set forth in my Patent No. 1,072,927, dated Sept. 9, 1913, that is to say in the following manner: The matrix-basket is moved toward the fixed frame by 95 rotating the coupling-rod 16 (Figs. 1 and 2). The thumb disk or cam 17 mounted at the lower end of coupling-rod 16, as shown in Figs. 1 and 2, carries a slanting face 34 on one side. When the cam is rotated in the 100 direction of the arrow (Fig. 2), the face 34 acts on a rod 35 (Fig. 1) and presses it downward; the end of this rod 35, presses on the end 32¹ of the arm 32 (Figs. 1, 2 and 8), and moves this end downward, thereby 105 rocking the arm 32. Consequently the arm 32 being now disengaged from the roller 33, the lever 30 is unlocked and since this lever is connected to the cage A, the spring 28 can now operate and displace the shaft 110

1, so that the collar 70 of the same lies against the bearing 22. In consequence of the displacement of the shaft 1, the entire cage is displaced, and the two-armed lever 5 30 is rocked, so that the arm 32 lies with its end 32² on the roller 33.

Referring more particularly to Figs. 1 and 8, it is to be noted that the hook-lever 37 is adapted to slide over a pulley 42 fixed 10 on the machine frame. When the nose of hook-lever 37 strikes the pulley 42, said hook becomes disengaged from stop 38, leaving said stop in the position indicated in full lines in Fig. 8. When the mold carrier 10 15 is tilted upward into the casting position indicated in dotted lines, the hook-lever 37 rides over the pulley 42, being elevated sufficiently thereby to resume, at the end of its stroke, the above operations for tripping 20 the arm 32 and the stop 38. In order to repeat the casting of the same line without disturbing the same under the conditions given in my said Patent No. 1,072,927, I provide a lever 39 (Figs. 1 and 8) which can 25 be rocked by hand or foot, on which lever there is a sliding piece 40 which by said lever 39 can be raised in front of stop 38 on lever 30 so that the hook-lever can not engage with the stop 38 and rock the lever 30 30 so as to displace the matrix bars.

When the coupling-rod 16 or the cam 17 is rotated, the lifter 14 and the stop 15 are to be simultaneously pushed forward into the path traversed by the matrix-bars. The cam 17 presses against the sliding-carriage 19 when it is rotated and the latter lies against the one arm of a two-armed lever 18. The end of the other arm of this lever 18 engages a slot 18' of plate i' , as shown in Fig. 5. Said plate i' is provided with a guide-slot i^2 which is engaged by a guide pin i , said plate i' carrying the plate or lifter 14. By these means the lifter 14 is guided rectilinearly in such a manner that it is pushed forward (see the dotted position in Fig. 5) or backward by rocking the lever 18. When the coupling-rod is rotated backward and when the cam 17 no longer lies against the carriage 19, a spring 43 draws back the lifter-bar 14. This carriage 19 acts in the known manner on a double lever 18 as soon as the coupling rod is turned, whereby the matrix cage is moved toward a stop 22 on the stationary frame and a stop 15 is advanced. The stop 15 is pushed forward by the matrix-cage A itself. On the matrix frame A is fulcrumed at 44¹ a two-armed lever 44, one of whose ends bears against the lever 46. A shoulder or stop of this lever engages in the notch 48 (Fig. 2) of a rod 49. The stop 15 is connected with a two-armed lever 20 which is pivoted at 50. The end of the lever is bent up angularly to form a slanting face 51. The lever 46 lies against this face 51. Now when the

cage is put into gear by rotating the coupling-rod 16, the cam 17, on said coupling rod 16, the cam 17, on said coupling rod acts on the lever 44 which, being fulcrumed or fastened on the matrix-frame A, is shifted with the same and thereby actuates the lever 46 which is thus forced against the upwardly bent end 51 of the two-armed lever 20, rocks the latter and pushes the stop 15 forward. 70

The stop 15 must be pulled back every time as soon as a word is composed in one sort of type and has to be pushed onto the strip 9. This is effected by depressing the space-key 21. The latter presses, by means of a rod 63, on the end of a lever 62 which is connected with the lever 20 of the stop 15 by a rod 64 in such a manner that this lever 20 is rocked and the stop 15 is drawn backward. One arm of the lever 62 is for this purpose connected to a rod or bar 64, best seen in Figs. 2 and 9, which rod or bar is formed at its free end with a hook 64' which passes over and engages the lever 20 which actuates the stop 15 in such a way that, on depressing the rod 63, the lever 20 is rocked to withdraw the stop 15, through the medium of the rod or bar 64, which is withdrawn to the right as rod 63 is depressed, as will be apparent from an inspection of Fig. 2 taken in connection with Fig. 9.

As best shown in Figs. 2, 3 and 9, the rod or bar 64 is pivoted at its one end on a boss extending from the rear of rod 49, one arm 100 of the lever 62 being jointed to the rear of said rod 49, at 49' as best shown in said Figs. 2, 3 and 9. A coiled spring 65 encircles the rod 49 and bears at one end against the fixed post 65' and at the other against an abutment 65² on the rod 49, thereby tending to urge the said rod 49 forward to the left in Figs. 2, 3 and 9. By pressing on the rod 63, therefore, the outwardly extending arm of the lever 62 is depressed, thereby pulling 110 back to the right the rod 49 and putting spring 65 under tension. By thus pulling back the rod 49, the lever 46 is rocked on its pivot 46², which is made possible by the fact that the lever 46 has been somewhat withdrawn from lever 44. This withdrawal of lever 46 from lever 44 is due to the fact that when the basket is put into gear by the rotation of the coupling rod 16, the pivot 46² of said lever 46 is concurrently shifted, 120 thereby rocking lever 46 on the end engaging notch 48 on rod 49 until it clears the end of lever 44. When the pressure of the rod 63 on lever 62 is released, the spring 65, being also released, returns the rod 49 125 to its original position, thereby rocking the lever 46 on its pivot 46², thereby, through the medium of the lever 20, returning the pin 15 to its original forward position, against the stress of the weaker spring 52.

On the double lever 18 is pivoted a vertical plate i' with a slot with which engages a pin i . The plate i' carries the raising or lifting bar 14. By rocking the double lever 18 the plate i' is shifted and thereby the lifter 14 is brought from the position shown in full lines in Fig. 5, into the position shown in dotted lines.

If mixed type is to be set, the cage is thrown in by rocking the coupling rod, and in that way the stop 15 and the lifter 14 are advanced. This is effected by rotating the coupling-rod 16 with it the cam 17 thereby depressing the arm 32, so that the spring 15 can displace the cage, the consequence of which is that the pin 15 is simultaneously pushed forward because the cam under these conditions strikes against the carriage 19 and shifts the same. The lifter 14 is also simultaneously pushed forward by the rotation of the cam 17. If the keys are now depressed, the matrix-bars run up the lifter and are thereby raised, so that the lower matrix comes into the position for casting. The matrix-bars are, however, held by the projecting pin 15 and prevented from running farther onward. If the word which is to be cast in full-faced type is then composed, the matrix-bars forming this word are then pushed forward in the manner set forth in applicant's Patent No. 1,072,927, the pin 15 being withdrawn. This is effected by pressing on the space-key, whereby the pin 15 is withdrawn by means of the rod 63. When the space-key is released, the pin 15 is pressed forward again. A second word can then be composed in full-faced type. The setting or assembling the matrix-bars is then effected in the usual manner. The matrix bars are, however, not raised, but rest with their lower ends on the lifter 14.

When a number of matrices corresponding to the lower characters 13 has been arranged in the rear of stop 15, which is normally in the projecting position indicated in Figs. 2 and 4, this group of matrices is raised in the following manner: Pressure is exercised on the end of the bell crank lever 62 connected to the rod 64, by pressing the spacing key and by the intermediary of the rod 63. The rod 64 is provided with a projection a pivoted to a lever c pivoted at b . The said lever is provided at its lower end with a projection d . On the lever 18 is pivoted at c a second lever f provided with a projection g corresponding to the projection d . As soon as the cage is thrown in, and consequently the lever 18 turned, the projection g will be situated above the projection d . If, by depressing the spacing key, the rod 64 is pulled in the direction of the arrow shown, the lever c will be rocked about fulcrum b , and in that way the lever f rotated about e so that the end of the rod f engaging at h with the bar 14, will be

pressed downward and in that way the bar turned about its guide pin i from the position shown in dotted lines in Fig. 5, into the position shown in chain dotted lines. The whole group of matrices will then be raised at the same time. At the same time the stop 15 is also withdrawn in the known manner, so that the group moves up to the holding bar k by its own weight. The arrangement could also be such that the advance and the raising of the lifting bar 14 would be effected by depressing the spacing key, in which case the thumb disk 17 would be connected to a rod connected to the spacing key.

In order to prevent the matrix bars, when moving on to the holding bar k , from assuming an angular position, or falling slightly out of the vertical plane of the line, which might take place as they have not an invariable support on their guide wires the recess l of the matrix bars is undercut at the top as shown in Fig. 5. In that case the holding bar k must be provided with a suitable projection. The matrix bars are thus held by means of half a dove-tailed guide, so that they cannot fall out of the vertical plane.

What I claim as my invention and desire to secure by Letters Patent is:—

1. In a matrix setting and line casting device the combination with matrix bars, a stop for said matrix bars, means for withdrawing said stop and a lifter for raising said matrix bars, of means operated by said withdrawing means for raising said lifter.

2. In a matrix setting and line casting device the combination with matrix bars, a stop therefor, means for withdrawing said stop, a lifter for raising said matrix bars and a shiftable support for said lifter, of means for rocking said support for raising said lifter.

3. In a matrix setting and line casting device the combination of matrix bars having undercut grooves therein, a stop for said matrix bars, means for withdrawing said stop and a lifter for raising said matrix bars, means operated by said withdrawing means for raising said lifter, a holding bar and a projection on said holding bar, said bar and projection being adapted to enter said undercut grooves when said matrices are raised, as set forth.

4. In a matrix-setting and line casting device, the combination of matrix bars, a stop for said matrix bars and a lifter for raising said matrix bars, with means for advancing the stop to arrest the matrix bars and for advancing the lifter, means for withdrawing the stop and means operated by said withdrawing means for raising the lifter.

5. In a matrix setting and line casting device the combination with matrix bars, a

stop for said matrix bars, means for withdrawing said stop and a lifter for raising said matrix bars, of means operated by said withdrawing means for rocking the lifter 5 upward.

6. In a matrix-setting and line casting device, the combination of matrix bars, a stop for said matrix-bars and a lifter for raising said matrix bars, with means for advancing the stop to arrest the matrix bars and for advancing the lifter, means for withdrawing the stop and means operated by said withdrawing means for rocking the lifter upward.

15 7. In a matrix-setting and line forming device, the combination of matrix-bars, a stop for said matrix-bars and means for withdrawing the stop and a sliding and rocking lifter, with a lever and connections

20 for advancing the stop and the lifter, means for rocking said lever, and means connected

with the lever and the lifter for rocking the lifter upward as the stop is withdrawn.

8. In a matrix-setting and line casting device, the combination of matrix-bars, a 25 stop for said matrix-bars and means for withdrawing the stop and a sliding and rocking lifter, with a lever and connections for advancing the stop and lifter, means for rocking said lever, a second lever fulcrumed 30 on the first lever and connected to the rocking lifter, and means for rocking the second lever and thereby rocking the lifter upward as the stop is withdrawn.

In testimony whereof I have signed my 35 name to this specification in the presence of two subscribing witnesses.

JULIUS DORNETH.
